UNITED STATES PATENT OFFICE.

LAWRENCE GRIFFITH, OF YONKERS, NEW YORK, ASSIGNOR TO THE HALL SIGNAL COMPANY,
A CORPORATION OF MAINE.

MECHANICAL MOVEMENT.

No. 873,426.

Specification of Letters Patent.

Patented Dec. 10, 1907.

Application filed March 31, 1905. Serial No. 253,048.

To all whom it may concern:

Be it known that I, LAWRENCE GRIFFITH, a citizen of the United States of America, residing in the city of Yonkers, county of 5 Westchester, and State of New York, have invented certain new and useful Improvements in Mechanical Movements, of which the following is a specification, reference being had therein to the accompanying drawings.

My invention relates to mechanical movements and its object is to produce a stroke of the working part greater than that of the part acted upon by the force applied and 15 when fluid or gas under pressure is the force used to provide means whereby the loss by leakage may be greatly reduced or done away with.

The invention is particularly applicable in 20 the operation of railway traffic controlling devices and I hereinafter describe it in connection with a railway signal having reference to the accompanying drawings in which similar characters of reference indicate similar 25 parts throughout the various views of which.

Figure 1 is a vertical section of my device, its connection with the railroad being shown diagrammatically, and Figs. 2, 3 and 4 are detail views of modifications.

30 1 is the semaphore blade of a railway signal. It is held in its normal or "danger" position, that shown in the drawing, by counter balance 2. The upward movement of rod 3, throws blade 1, down or to "safety" 35 position in the usual manner.

4 is the casing for the device and is adapted to inclose the storage tank 5, reducing valve 6, controlling valve 7, with electromagnets 8 and 9 and battery 10 for operating valve 7.

The section 11 of the railway tracks is insulated by insulated rail-joints, 12, and the circuit of battery 13 is normally closed. The presence of wheels 14 on said section 11 45 short-circuits battery 13, thereby deenergizing magnet 9, the armature of which is returned to normal position by gravity, spring, or similar devices, and opening valve 7. Within said casing 4 is also contained

50 my new device which I now proceed to describe. 15 is a casing for the lower part which supports diaphragm 16. Pipe 17 communicates with said casing 15 beneath said diaphragm 16 and with valve 7, so that 55 when valve 7 is opened the force passing

therethrough will be exerted on said diaphragm and raise it. Resting on said diaphragm 16 and working with it is block 18, the upper part of which fits tightly and is adapted to work as a piston within the part 60 15^a of the casing 15. The part 15^b of the casing is smaller than the part 15^a and within it piston 20 is adapted to work. Within the casing and between piston 20 and block 18 is a liquid 19. 21 is a pipe and valve for supplying or removing said liquid 19. As the part 15^b with its piston 20 is smaller than the part 15^a with the block 18 an upward movement of block 18 will produce a greater upward movement of piston 20 and conversely 70 a downward movement of piston 20 will produce a lesser downward movement of block 18. Piston 20, carries rod 3 above mentioned.

In Fig. 2, I have shown the force from 75 pipe 17 extended directly on block 18 without the intervention of a diaphragm. When the diaphragm is used as in Fig. 1 there is none of the leakage which occurs from the operation of a piston within a cylinder. 80

In Fig. 1 by dotted lines 23, I have indicated how the invention may be connected with a pneumatic or other fluid pressure system instead of with the storage tank 5. It being understood that the pipe represented 85 by 23 may lead to any of the well-known fluid-pressure devices.

I do not limit the invention to the above described means of moving block 18. For instance, as shown in Fig. 3, it may move 90 by the action of armature 24, when electromagnet 25 is energized.

Another form of my invention is shown in Fig. 4. The part 15^a of casing 15 approaching the part 15^b is conically shaped and is 95 filled with anti-friction balls 22. Of course, instead of liquid or balls any substitute which will readily change its form under pressure may be used without departing from my invention. 100

Having thus described my invention what I claim and desire to secure by Letters Patent is:—

1. In a railway traffic-controlling device, the combination of a part to be moved, a 105 supply of liquefied gas, means for operating the part to be moved by the gas, which consists of a casing covered by a diaphragm said diaphragm being mechanically connected with a moving part of a mechanical move- 110

ment comprising two communicating chambers of unequal cross-section a block adapted to fit and work in each of said chambers and a substance adapted to fill the space between 5 said blocks and to readily change its form so as to pass from one chamber to the other and to transmit motion to one of said blocks as the other is moved.

2. In a railway traffic-controlling device, 10 the combination of a part to be moved, a supply of liquefied gas, means for operating the part to be moved by the gas, which consists of a moving part of a mechanical movement comprising two communicating cham-

bers of unequal cross-section a block adapted 15 to fit and work in each of said chambers and a substance adapted to fill the space between said blocks and to readily change its form so as to pass from one chamber to the other and to transmit motion to one of said blocks as 20 the other is moved.

In testimony whereof I have hereunto set my hand, this 28th day of March, 1905.

LAWRENCE GRIFFITH.
